UNITED STATES PATENT OFFICE.

FRANK FELBINGER, OF MILWAUKEE, WISCONSIN, AND ALEXANDER E. CAFMEYER, OF CHICAGO, ILLINOIS.

FLUID-COMPRESSOR.

No. 893,913.

Specification of Letters Patent.

Patented July 21, 1908.

Application filed January 7, 1907. Serial No. 351,107.

To all whom it may concern:

Be it known that we, FRANK FELBINGER, a citizen of the United States, and a resident of the city of Milwaukee, in the county of Milwaukee, in the State of Wisconsin, and ALEXANDER E. CAFMEYER, a citizen of the United States, and a resident of the city of Chicago, in the county of Cook and State of Illinois, have invented certain new and useful Improvements in Fluid-Compressors, of which the following is a specification.

Our invention relates to high compression apparatus and particularly to those devices which are used for compressing carbonic anhydrid for refrigerating purposes.

The extreme high pressure at which the gas is handled makes it difficult to attain the highest degree of economy and efficiency in the compressors used, while more or less waste of material has heretofore been found unavoidable. In our invention we are able to eliminate practically all clearance space in the cylinder and its valve connections, the valves are sealed against connection with the air, while we provide means by which all gas wastage from the cylinder is trapped and forced back into the same and into the distributing system.

Our apparatus also comprehends means for supplying oil to the working parts of the apparatus, and making a complete lubrication thereof, thus reducing the frictional resistance to a minimum.

The principles of our invention are illustrated in the drawings, in which:

Figure 1 shows a vertical longitudinal section; Fig. 2 is an end view of one of the cylinder heads; Fig. 3 is a cross section of Fig. 2 on the dotted lines 3—3; Fig. 4 is a view of one of the piston rings looked at in the line of the piston rod; Fig. 5 is a section thereof on the line 5—5 of Fig. 4; Fig. 6 shows a spring piston ring; Fig. 7 is a top view of the same; Fig. 8 shows two views of a segmental block or wedge for said piston ring, and Fig. 9 is an enlarged view partly in section of the gland sleeve.

Further describing our invention with reference to the drawings, in which like characters of reference denote like parts throughout: 1 is a substantial base plate upon which is mounted, and preferably formed integrally therewith, the cylinder 2. The same is provided with a bushing 3 which is securely fastened to it, and which is accurately bored to

receive the piston head and packing rings. At the end of said cylinder, farthest from the source of power, is attached the cylinder head 4, which is provided with the flanges 5, by which it may be attached to the cylinder. The said head is provided with a deep recess 6, preferably of rounded contour. Said head may have the annular flanges 6' surrounding the recess 6 and adapted to be seated in a corresponding annular groove in the end of the bushing 3. Communicating directly with the recess 6 in the cylinder head are valve chambers 7 in which are seated valve casings 8. The latter are held securely in place by means of the sealing bonnets 9, which may be attached to the piston head by the tap bolts 10. At the other end of the cylinder is a head 15, which, as far as already described, is like the other head. It is, however, centrally perforated to allow the passage of the piston rod 16 and is further modified as will hereinafter be described.

Connected with the valve chambers on each of the piston heads and preferably formed integrally with the latter are short connecting pipes provided with flanges 17 or other suitable means of connecting them to the circulatory system. We prefer to place the inlet valves, illustrated by 20, on one side of the apparatus and the outlet valves 21 on the other side of the apparatus, communicating respectively with the connecting pipes 18 and 18'. The said valves, as preferably constructed, are inclosed in casings 25 which are shaped to correspond with the internal form of the valve chambers 7. The inlet and outlet valves are similar in construction and centrally of their casings may have a compartment 27 in which the springs 28 are inclosed by means of the screw plugs 29. The inlet valve 20 has a head 30 resting on the seat 31 and adapted to play into the recess 6. The outlet valve 21 has a head 34 resting on the seat 35 and adapted to play into the valve casing 25. Both heads should play up to the cylinder bore and be contoured to correspond therewith.

In addition to the features described, which are common to both the cylinder heads, the one through which the piston rod passes may be substantially in the section of a truncated cone. An elongated stuffing box or gland 39 may be seated in the end of said cylinder head upon the fiber or other packing 40 and securely attached thereto by

means of the flanges 41 and the tap bolts 42. To insure perfect rigidity it should be further supported by the oiler standard 43 secured to the base 1. Into the lower part of the 5 stuffing box should be placed metallic packing 44 of any suitable kind and next thereto should be inserted the sleeve 44'. Above the sleeve may be placed any good quality of soft packing 45. The whole is then screwed 10 securely into place by means of the gland nut or cap 46 and the follower 47.

The sleeve 44 shown in enlarged section in Fig. 9 should have its outer diameter correspond accurately to that of the stuffing box. 15 It is reduced in size through a considerable part of its length by the groove 50, while a corresponding and similar groove 51 is formed on the inside of the sleeve. The two grooves are connected by numerous small 20 openings 52. The end of a pipe 55 is inserted into the stuffing box opposite the groove 50 in the sleeve 44. The said pipe is connected to an oil force pump, not shown, by which oil under a high degree of pressure may 25 be forced as hereinafter described. A tube 60 is similarly inserted into the side of the stuffing box opposite groove 50 and this is carried outside of the stuffing box to a connecting point as 61 with a duct 62 in the cylinder 30 head. The latter is provided with an inlet or relief valve 63 similar in construction to those heretofore described and, being like them securely sealed by a cap 64, into the material of the cylinder head. The said duct 35 62 extends into said valve chamber; while an outlet therefrom 65 opens into the cylinder bore 3'. A piston head comprising enclosed ends 6", 6" contoured to correspond to the inner shape of the recessed cylinder 40 heads, is also provided between the said contoured ends with bull rings 70, details of which are shown in Figs. 4 and 5. These are perforated with an axial bore 71 to take the piston rod and are turned down to form a 45 neck 72. On the said neck is mounted a ring 73, which may be secured in place by screws or other means. A segment shaped wedge shown in Fig. 8 may have an upper portion 75, while the portion 75' fills the space 50 on the neck of the bull ring between the ends of the applied ring 73. Over the whole, as thus constructed and assembled, is sprung the ring 76 somewhat larger than the bore of the cylinder. The construction of said ring 55 is illustrated in Fig. 7 in which the open space 76' is adapted to embrace the portion 75 of the wedge, while the continuous parts 76" are seated on that portion 75' of the wedge which rests on the bull ring. 60 The operation of the apparatus above described may be explained with reference to a simple refrigeration system, in which the outlet pipes of the apparatus are connected with a piping system by which the compressed 65 and heated fluids are conveyed to a condenser

in which they are cooled and assume, in the case of carbonic anhydrid, the liquid form. When the pressure is removed at the condenser or storage tank such fluids by their expansion and evaporation are adapted to 70 refrigeration and when their power therefor is exhausted they are led under comparatively low pressure back into the inlet pipes of the apparatus wherein they are compressed and continue on their rounds as before, making a series of continuous operations. 75

Assuming the piston rod to be in the position shown in Fig. 1 and the cylinder bore in the rear of the piston head to be filled with gases to be compressed, the motion of the 80 piston head to the other end of the bore will compress the gases, forcing them through the outlet valve in the head 15 to the outlet pipe, not shown. At the same time the space in front of the cylinder is filled with gases drawn 85 through the inlet valve of the pipe 18, while the return of the cylinder forces the same through the outlet pipe 18'. The rounded ends of the piston head corresponding to the rounded recesses in the cylinder heads work 90 very closely therein, allowing, if the mechanism is properly adjusted, very little loss of efficiency from clearance space. The arrangement of spring packing upon the bull 95 rings permits little or no wastage past the cylinder head, while any wastage which may occur through the cylinder rod packing upon the return of the head will be trapped by the recess or groove 50 in the sleeve 44. As the head returns to the other end of the cylinder 100 the comparative vacuum formed causes such wastage to pass through the duct 62 until an equilibrium of pressure is established with that in the inlet pipe at this end of the cylinder, the egress of gases therefrom and the return of gases through said duct being checked 105 by the operation of the valve 63. It will thus be seen that any accumulation of gases under high pressure within the gland will be prevented as the same are immediately returned to the circulatory system with each 110 return stroke.

The sleeve 44 performs a further function. Lubricating oil may be forced through the 115 pipe 52 under pressure by any preferred form of oil force pump. Entering the annular recess 50 it is free to pass through the openings 52 to the inner groove 51 on the inside of the sleeve, the latter being filled at all times with the oil. A complete lubrication of the piston rod is effected, the oil thus further aiding in holding the gas pressures which may be presented. Any surplus of oil is forced in common and mingled with the wastage which 120 may be trapped by said sleeve through the pipe 60 and the duct 62 to the inside of the cylinder head, where it thoroughly lubricates the spring packing and other wearing parts. Any accumulations of oil will be 125 ejected from the cylinder head through the 130

outlet pipes and may be drained from the system to which they are attached by traps suitably placed.

Having thus described our invention with reference to its embodiment in a practical machine, we claim and desire to secure by Letters Patent the following:

1. In a compressor, a cylinder having a head, and a piston working in said cylinder, a waste trap adjacent to the piston rod, a duct or pipe to connect the trap directly to the cylinder bore through said cylinder head, and a valve in said duct within the cylinder head to control the flow of wastage to the cylinder and to force it therein by the action of the piston.
2. In a compressor, a cylinder having a head, and a piston working in said cylinder, a sleeve surrounding the rod of said piston having a recessed portion constituting a waste-receiving chamber, a tube or duct extending through the cylinder head and connecting said chamber to the cylinder bore, and means in the cylinder head for controlling the flow of wastage through said tube or duct.
3. In a compressor, a cylinder having a head and a piston working in said cylinder, a sleeve surrounding the piston rod and provided with an annular recess constituting a waste-receiving chamber, and a tube or duct extending through the head communicating with the cylinder, a pipe connecting said duct with said waste-receiving chamber, and a valve in the cylinder head to control the flow of wastage through said tube or duct.
4. In a compressor, a cylinder having a head, and a piston working in the cylinder, a stuffing box for the piston rod, a sleeve in the stuffing box having a recessed portion constituting a waste receiving chamber, a packing at each end of the sleeve, a relief duct extending through the cylinder head and establishing communication between the cylinder

bore and said waste-receiving chamber, and a valve in the cylinder head controlling the flow through said duct.

5. A piston packing for the piston of a compressor comprising a bull ring having a neck, a split band mounted on the neck and having a segmental cut-away portion in the periphery thereof, and a segmental filler wedge filling the cut-away portion of said ring.

6. In a compressor having a cylinder and a piston working therein; a stuffing box for the piston rod, a trap in the stuffing box adjacent to the piston rod to collect waste oil and gases, a duct to connect the trap to the cylinder bore, a valve in said duct relatively nearer to the cylinder bore than to the trap, and a sealing bonnet for said valve.

7. A piston packing for the piston of a compressor comprising a bull ring having a neck, a split band fixed on the neck and having a space between its ends, a split ring on the band having a segmental cut-away portion and a segmental filler wedge having an upper and a lower portion, the upper portion fitting in the segmental cut-away portion of the split ring and the lower portion fitting in the space between the ends of said split band.

8. A piston packing for the piston of a compressor comprising a bull ring having a neck, a segmental band on the neck, a spring ring having an open space mounted on the band, and a filler wedge adapted to fill the open space in the spring ring and having a flange to fill the space in the segmental band.

In witness whereof we have hereunto set our hands this 31st day of December A. D. 1906, in the presence of two subscribing witnesses.
